(57) **CLAIM**

The ornamental design for an LED lamp as shown and described.

DESCRIPTION

FIG. 1 is a top right perspective of the LED lamp showing my new design;

FIG. 2 is a bottom left perspective view thereof;

FIG. 3 is a top view thereof;

FIG. 4 is a front view thereof;

FIG. 5 is a right side view thereof;

FIG. 6 is a left side view thereof;

FIG. 7 is a back view thereof; and,

FIG. 8 is a bottom view thereof.

The broken lines in FIGS. 1-7 of the drawings are for purposes of illustrating portions of the led lamp, which form no part of the claimed design.

1 Claim, 8 Drawing Sheets
